CLAIM

The ornamental design for a wall plate, as shown and described.

DESCRIPTION

FIG. 1 is a photographic perspective view of a wall plate for a switch illustrating my new design.

FIG. 2 is a photographic front elevational view of the wall plate of FIG. 1.

FIG. 3 is a rear elevational view of the wall plate of FIG. 1.

FIG. 4 is a side elevational view of the wall plate as in FIG. 1.

FIG. 5 is an end plan view of one end of the wall plate of FIG. 1.

FIG. 6 is an end plan view of the other end of the wall plate of FIG. 1.

FIG. 7 is a vertical elevational view of a wall plate for a wall receptacle illustrating my new design, the surface decoration being shown only in one corner segment only for ease of illustration.

FIG. 8 is a vertical elevational view of a wall plate for two side-by-side switches illustrating my new design, the surface decoration being shown only in a corner fragment as in FIG. 7.

FIG. 9 is a vertical elevational view of a wall plate for a switch and duplex receptacle, only a portion of the decorative motif shown for ease of illustration.
